CLAIM

The ornamental design for a pre-recorded optical disk, as shown and described.

DESCRIPTION

FIG. 1 is a front side view of a pre-recorded optical disk showing our new design;

FIG. 2 is a front and edge perspective view of the disk of FIG. 1;

FIG. 3 is an edge view of the disk of FIG. 1;

FIG. 4 is a rear side view of the disk of FIG. 1; and, FIG. 5 is a rear and edge perspective view of the disk of FIG. 1.

A characteristic feature of the design of the optical disk as shown is that it differs from the appearance of conventional pre-recorded optical disks of the CD-Audio and CD-ROM format, principally in that metallized region of the disk stops well short of the outer diameter, to leave a relatively wide unmetallized outer annulus.
